UNITED STATES PATENT OFFICE

HOWARD WILLIAM SHELDON, OF EAST ORANGE, NEW JERSEY, ASSIGNOR TO VACUUM OIL COMPANY, OF NEW YORK, N. Y., A CORPORATION OF NEW YORK

APPARATUS FOR REMOVING CARBONACEOUS MATERIAL FROM OIL APPARATUS

Application filed July 11, 1929. Serial No. 377,447.

This invention relates to an apparatus employed primarily, although not necessarily exclusively, in the refining and cracking of petroleum oils, and has to do with means for removing coke from various portions of the apparatus, especially the soaking drums or reaction chambers used in connection with cracking stills. For example, the oil and vapor from a pipe still is passed into this soaking drum or reaction chamber where the oil evaporates, due to self-contained heat, and most of the coke produced during the process is deposited.

During the operation of the apparatus the accumulation of coke ultimately fills the chamber, so that it becomes necessary to remove it. The removal of this coke is difficult, and many means have been devised for it.

In accordance with the present invention, there is provided within the chamber a plurality of independent flexible metal cables suspended from various points located at the top of the chamber. The cables are installed in such a manner that the coke can be broken up progressively by withdrawing each of the cables separately, from the top downwardly.

The invention will be more readily understood from a consideration of the accompanying drawings in which,

Figure 1 represents a central vertical section through the evaporating chamber on the line 1-1 of Figure 2, illustrating the location and manner of attaching the cables to the top and bottom of the chamber.

Figure 2 is a cross section through the line 2-2 of Figure 1.

Figure 3 is a fragmentary view, illustrating one manner of attaching the flexible cables to the top of the chamber, and showing a device for holding the respective cables in position.

Figure 4 is a detail view, illustrating a device for breaking up the coke.

In the drawings, Fig. 1 represents the cylindrical reaction or evaporating chamber 10 as provided with oil inlets 11, either at the top or bottom of the chamber. The chamber 10 is also provided with a vapor outlet 12, through which the vapors from

the chamber may pass to suitable dephlegmators and condensers. The top and bottom of the chamber 10 are provided with central manholes, closed by heads which are designated by the numerals 13 and 14, respectively, these heads being removable to permit access to the interior of the chamber 10.

Attached to the top of the chamber 10 are concentric rings 15, from which are suspended flexible vertical cables 16, of which any desired number may be supplied. In practice, these rings and cables are usually substantially equi-distant. There is also a row of cables 17, firmly attached to both the upper and lower ends of chamber 10, upon which cables the spirally wound cable 18 is hung. The cable 18 may be attached to the vertical cables 17 by means of tie wires or other suitable devices which are easily broken as the cable is removed.

The means for connecting each cable 16 to one of the concentric rings 15 is illustrated in Figure 3. By referring to this figure it will be seen that the tie wire 19 passes through a hole in the ring 15, the tie wire being also secured in any convenient manner to an elbow-shaped clamp 20 through which the cable 16 passes. For the purpose of attachment the clamp 20 may be provided with an eye 21 through which the tie wire 19 may pass. The clamp 20 serves to hold the cable 16 in proper position.

The cables 16 may be provided with lugs 22, conveniently diamond-shaped with sharp corners, although the particular shape is not essential, which will tend to cause the choke to be broken up into relatively small fragments as the cables are withdrawn. The lug 22 is secured to the cable 16 in any desired convenient manner. Each of the cables 16 is supplied with a means, such as a ring 23, which will permit the cable to be grappled at its upper end for its removal. The cables 17 are similarly provided with rings 24, and the coiled cable 18 with a ring 25.

In order to hold the cables in position during the first few hours of the operation, that is, until the lower ends are embedded in coke, the cables may be attached to the bottom of

the chamber. For this purpose, each cable 16 is fitted at its lower end with a ring 26, each ring engaging a hook 27, the hooks 27 being attached in the proper position on the inside of the bottom of the chamber. These hooks have their open ends toward the center of the chamber, so that when the cables are withdrawn, through the lower manhole, they will automatically unhook.

10 When carbon is to be removed from the chamber the lower manhole 14 is removed and the flexible cable 18 is withdrawn. As this cable is withdrawn it will break out the coke and will core a relatively large vertical passage through the mass. The upper manhead 13 is then removed and the inner row of cables 17 is detached from the inside of the manhead nozzle and pulled down through the opening in the center of the coke mass by 15 means of a suitable winch. The cables 16 are then removed by passing a suitable pulling means up through the bottom manhole to the top of the drum and attaching it to each ring 23, one after another, taking them in 20 the order of their concentric circles until the entire lot has been removed, each cable being pulled, from its upper end, downwardly through the lower manhole.

What I claim as my invention and desire 30 to secure by Letters Patent is:

1. The combination, with an upright cylindrical chamber provided with central manholes at both ends, of means, for removing carbon from the chamber, comprising a plurality of independent flexible members suspended vertically in the chamber and at different distances from the axis thereof, each of said members being attached, near its upper extremity, to the top of the chamber and 35 having a free end extending inwardly, from the point of attachment, to a point near the upper manhole, so that each flexible member may be engaged in turn at said end and separately pulled downwardly through the lower 40 manhole.

2. The combination set forth in the preceding claim, together with hooks, on the bottom of the chamber, for securing the lower ends of the flexible members, each hook opening 45 toward the middle of the chamber so that the flexible member may be freely disengaged therefrom when pulled through the lower manhole.

HOWARD WILLIAM SHELDON.
